UNITED STATES PATENT OFFICE.

FRANCIS B. JOY AND CHRISTIAN H. VOGEL, OF DETROIT, MICHIGAN, ASSIGNEES TO THE DETROIT HEATING & LIGHTING COMPANY, OF DETROIT, MICHIGAN, A CORPORATION OF MICHIGAN.

BUNSEN BURNER.

1,276,075.

Specification of Letters Patent. Patented Aug. 20, 1918.

Application filed May 4, 1918. Serial No. 232,430.

To all whom it may concern:

Be it known that we, FRANCIS B. Joy and CHRISTIAN H. VOGEL, citizens of the United States of America, residing at Detroit, in the county of Wayne and State of Michigan, have invented certain new and useful Improvements in Bunsen Burners, of which the following is a specification, reference being had therein to the accompanying drawings.

This invention relates to gas burners and more particularly to gas burners of the well-known Bunsen type.

It is the object of the invention to provide an improved mounting for a Bunsen burner, an improved adjustment means for regulating the air supply thereto, and to embody various other structural features in a Bunsen type of burner to increase the efficiency thereof and decrease the cost of production.

In the accompanying drawings:

Figure 1 is a perspective view of the burner, and;

Fig. 2 is a view of the same in vertical section.

In these views the reference character 1 designates a base, centrally orificed as indicated at 2, and 3 is a standard formed integrally with said base at one side of said orifice and curved to position a barrel 4 at the upper end of said standard above the orifice of the base. Within said barrel there is fitted a valve casing 5, the upper portion of which is enlarged to bear upon the top of the barrel, as indicated at 6. The casing 5 is formed with an axial passage 7, the lower portion of which is threaded to be engaged by the valve stem 8. The upper extremity of said stem is tapered to engage a valve seat 9 surrounding a restricted gas outlet in the top of the casing 5 and the barrel 4 is integrally formed with a nipple 10 for connection with a gas supply hose (not shown), the passage through said nipple having communication with the axial opening of the casing through an orifice 11 in said casing. To provide for a flow of

gas from said orifice to the outlet at the top of the casing, the upper portion of the stem 50 9 is of reduced diameter, as indicated at 12.

The enlarged upper portion of the casing 5 has screw-threaded engagement with the lower end of a suitable mixing chamber 13 which has formed therein, a circumferential series of triangular air induction orifices 14. The upper end of said mixing chamber communicates with and is rigidly connected to the lower extremity of a vertical tube 15 through which the mixture of 60 gas and air rises to the point of combustion.

By adjusting the parts 13 and 15 downwardly upon the casing 5, the size of the openings forming air inlets to the chamber 13 may be continuously reduced and even 65 entirely closed in a limiting position of said parts 13 and 15. An adjustment upwardly of said parts will continuously increase the size of the openings until, if desired, the entire area of the orifices 14 is exposed above 70 the casing. By employing a single standard to support the barrel 4, the knob 16, by which the valve stem is turned, is readily accessible.

What we claim as our invention, is:

1. In a gas burner, the combination with a base, of a barrel vertically mounted and spaced above said base, a valve casing carried by said barrel and formed with an axial passage, a valve engaging in said passage to close the same and projecting below said barrel, means for establishing a gas connection through the barrel and casing with said passage, and an air mixing chamber having screw-threaded engagement with 80 a projecting portion of said casing and having an outlet for the gaseous mixture, said chamber having a circumferential series of triangular openings for admitting air, said 85 openings being variably closed through rotative adjustment of the mixing chamber relative to the casing.

2. In a gas burner, the combination with a valve casing having an axial passage terminating in a gas outlet, and having a gas 95 inlet to said passage, of a valve controlling

the flow of gas through said passage, a mixing chamber having screw-threaded engagement with the casing and inclosing the gas outlet thereof, said chamber having a circumferential series of triangular air induction orifices adapted to be variably closed by the valve casing through rotation of said

mixing chamber, and an outlet tube for the gaseous mixture carried by the mixing chamber. 10

In testimony whereof we affix our signatures.

FRANCIS B. JOY.
CHRISTIAN H. VOGEL.
